US0D1040660S

(12) **United States Design Patent** (10) Patent No.: **US D1,040,660 S**
(45) Date of Patent: ** Sep. 3, 2024

(54) **EVAPORATOR BOTTLE**

(71) Applicant: **Thermacell Repellents, Inc.**, Bedford, MA (US)

(72) Inventors: **Adam Chojnacki**, Carlisle, MA (US); **Robert G. Holmes, Jr.**, Clinton, MA (US); **Steven M. Bourque**, Billerica, MA (US)

(73) Assignee: **Thermacell Repellents, Inc.**, Bedford, MA (US)

(**) Term: **15 Years**

(21) Appl. No.: **29/746,232**

(22) Filed: **Aug. 12, 2020**

(51) LOC (14) Cl. **07-01**

(52) U.S. Cl.

USPC **D9/519**; D9/572

(58) **Field of Classification Search**

USPC D9/563, 572, 573, 574, 575, 499, 549,

D9/550, 558, 424, 516, 519, 529

CPC B65D 1/0223; B65D 23/0878; B65D

2543/00092

(57) **CLAIM**

The ornamental design for an evaporator bottle, as shown and described.

DESCRIPTION

FIG. 1 is a perspective view of an evaporator bottle according to the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines depicting portions of upper and lower housing components are provided for location reference purposes and form no part of the claimed design.

1 Claim, 6 Drawing Sheets
